UNITED STATES PATENT OFFICE.

DE WATT PEPPER, OF NEW MILFORD, CONNECTICUT.

DESIGN FOR A DIVAN-FRAME.

SPECIFICATION forming part of Design No. 36,200, dated January 27, 1903.

Application filed December 26, 1902. Serial No. 136,745. Term of patent 3½ years.

To all whom it may concern:

Be it known that I, DE WATT PEPPER, a citizen of the United States, residing at New Milford, in the county of Litchfield and State of Connecticut, have invented and produced a new, original, and ornamental Design for a Divan-Frame; and I do hereby declare the following to be a full, clear, and exact description of the invention, such as will enable others skilled in the art to which it appertains to make and use the same.

The accompanying drawing shows a front elevation of my new design.

As shown in the drawing, the leading or material features of my design consist of the acanthus-like ornamentations 1, extending in reverse directions at the upper side of the middle portion of the top rail 2 at the back of the divan-frame, and the acanthus-like ornamentations 3, immediately below the ornamentations 1 and reversely arranged with respect thereto and likewise extending in opposite directions, the remainder of the rail 2 being left perfectly plain, the side frames 4

having their front portions generally diverging from top to bottom and bounded by compound curves, said front portions being intersected by horizontal and parallel groove-like portions 5, the acanthus-like ornamentations 6 on the front of the seat-frame 7 and extending in reverse directions, the rest of said seat-frame being left plain, and the feet 8, upon which the frame 7 rests at its ends, said feet having at their upper portions immediately beneath the frame 7 scroll-like ornamentations 9, while the feet themselves terminate in representations of toes 10.

Having thus described my invention, what I claim as new, and desire to secure by Letters Patent, is—

The ornamental design for a divan-frame, as herein shown and described.

In testimony whereof I affix my signature in presence of two witnesses.

DE WATT PEPPER.
